PORTABLE BARBECUE GRILL

Don Beeler, Chicago, Ill.

Application July 27, 1954, Serial No. 31,634

Term of patent 14 years

(Cl. D81—10)

*Fig. 4.Fig. 5.Fig. 6.*Fig. 1 is a plan view of a portable barbecue grill showing my new design, said portable barbecue grill being shown in open position;

Fig. 2 is a front elevational view thereof;

Fig. 3 is an end elevational view thereof;

Fig. 4 is a plan view showing the portable barbecue grill in folded position;

Fig. 5 is a front elevational view thereof; and

Fig. 6 is a side elevational view thereof.

The dominant features of the design are shown in solid lines.

I claim:

The ornamental design for a portable barbecue grill as shown and described.
